UNITED STATES PATENT OFFICE.

EDWARD SCHWARTZ, OF NEW YORK, N. Y., ASSIGNOR TO MANHATTAN ELECTRICAL SUPPLY COMPANY, OF JERSEY CITY, NEW JERSEY, A CORPORATION OF MASSACHUSETTS.

ELECTROMAGNET.

1,297,919.

Specification of Letters Patent. Patented Mar. 18, 1919.

Application filed August 31, 1918. Serial No. 252,162.

To all whom it may concern:

Be it known that I, EDWARD SCHWARTZ, a citizen of the United States of America, residing in the city, county, and State of New York, have invented a certain new and useful Improvement in an Electromagnet, of which the following is a specification.

My invention relates to electromagnets and particularly to electric buzzers, the object of my invention being to provide efficient, reliable, and readily adjustable buzzers of improved construction.

In the accompanying drawings,

Figure 1 is a plan of the buzzer in which my invention is illustratively embodied;

Fig. 2 is a front elevation thereof;

Fig. 3 is a section on the line 3—3 of Fig. 2; and

Fig. 4 is an elevation of the armature 20 alone.

As here shown the buzzer is mounted on an insulating base 10 to which it is secured by a pair of screws 11 and 12 taking into the base of the frame. The latter is preferably

25 stamped from sheet iron and bent to a general U-shape, the upright 14 rising at right angles from the rear margin of the base. A pair of arms 15 and 16 form the top of the frame parallel to the base and constitute 30 integral extensions at opposite ends of the upright 14. These arms are united at the front of the frame by a panel 17 offset upward at right angles thereto and having a central top flange 18 and a central downwardly projecting boss 19. A boss 20, alined with the latter, rises from the top of the upright 14. Core pins 21 and 22 pierce the upright 14 and support the electromagnet coils 23 and 24 on axes parallel with the base.

40 A resistance coil 25 to choke arcing at the armature contact, is supported at the top of the frame by a screw bolt 26 taking into the top flange 18 and is suitably connected between the magnet coils and the frame.

45 The armature 27 is struck from spring sheet metal and depends from the top flange 18 of the frame, to the front of which it is secured by a pair of clamping screws 28 and 29 which pass through the clamp plate 30, and a pair of slots 31 in the head 32 of the armature, so that the latter may be vertically 50 adjusted. In order to increase the flexibility of the vibratory portion of the armature and to maintain its spring action uniform in 55 various positions of adjustment, its body is

apertured at 33 to form a pair of spring arms 34 and 35 which connect the armature bar proper 36 with the head 32 thereof. Into this aperture 33, a tongue 37 projects from the head 32, and in adjusted position 60 alines with the bosses 19 and 20. This tongue forms an abutment against which the adjusting pin 38 bears. In the form here shown this pin has a threaded area 39 adjacent its knurled head 40 and works in a 65 tapped hole in boss 20, while the stem of the pin passes freely through the guide pole in boss 19 into engagement with the tongue 37. Riveted at 41 on the armature bar 36 is a bridge strap 42 carrying a platinum contact 43.

The coöperating contact 44 of the buzzer is also preferably of platinum in the form of a button at the end of screw 45. The latter is mounted in split standard 46, the offset 70 base of which is secured by screws 47 to a foot piece extension 48 of the frame base, but insulated therefrom by strips 49 of mica or the like.

The lead wires 50 and 51 are connected by 80 the binding screws 52 and 53 respectively, one, viz., 50, carried by terminal plate 54, and the other, viz., 53, carried by an arm 55 extending to one side of the split standard 46. The terminal plate 54 is insulated from 85 the frame of the buzzer and a lead 56 from one of the magnet coils is secured thereto at 57, in any suitable way, as for instance, by soldering. A third binding screw 58 is mounted in the lug 59 at one side of the upright 14 and affords an extension connection, if desired.

The arrangement indicated is particularly advantageous by reason of the fact that the pull of the magnets upon the armature bar 95 is equalized under all conditions due to the oscillation of the armature on an axis at right angles to the axes of the magnet coils and its location on a plane parallel to the plane of said axes instead of alined therewith, as is the common construction. The spacing of the armature bar from the magnet cores by the adjusting pin 38 does not affect the flexibility of the spring arms 34 and 35, the spring action of which is uniform under all conditions owing to their separation from the tongue 37 against which the adjusting pin bears. The mounting of the choke coil 25 above the armature frame 105 removes a disturbing influence from the field 110

of the electromagnet coils 23 and 24 and furthermore presents the manufacturing advantage of being an independent element which may be wound separately without interfering with the winding of either of the magnet coils. Its connection in the buzzer circuit is readily effected during assembly of the coils on the frame. The construction as a whole is simple and economical, the 10 parts are not easily disarranged and the armature is susceptible of very delicate adjustment due to the fact that the pin 38 and screw pin 45 bear against its opposite sides.

Variations in detail of construction will 15 readily occur to those skilled in the art, without departing from what I claim as my invention.

I claim:—

1. An electromagnetic buzzer comprising 20 a frame having a base, a standard rising from the rear margin thereof and a top extending forwardly from said standard and parallel to the base to form a substantially U-shaped frame, a pair of electromagnets 25 mounted on the standard within the frame and with their axes lying in a plane substantially parallel to the base, a spring armature depending from the top of the frame in front of the magnet cores, an adjusting screw supported by the standard and bearing against the rear of the armature to regulate the spacing thereof from the magnets, and an adjustable fixed contact 30 normally engaging the front of said armature to complete the buzzer circuit therethrough.

2. In combination with a construction such as specified in claim 1, a choke coil mounted on the frame above the top thereof and connected in the circuit of the magnet coils.

3. An electromagnetic buzzer comprising 45 a frame having a base, a standard rising from the rear margin thereof and a top extending forwardly from said standard and parallel to the base to form a substantially U-shaped frame, a pair of electromagnets mounted on the standard within the frame and with their axes lying in a plane sub- 50 stantially parallel to the base, a flange rising from the front edge of the frame top, a spring armature having its head rigidly secured to said flange and depending therefrom to a point in front of the armature 55 cores, an adjusting screw supported by the

standard and bearing against the rear of the armature to regulate the spacing thereof from the magnets, and an adjustable fixed contact normally engaging the front of said armature to complete the buzzer circuit 60 therethrough.

4. In a construction such as specified in claim 3, a choke coil mounted on said flange and overlying the magnet coils but above the top of the frame and connected in the 65 circuit of the magnet coils.

5. In an electromagnetic buzzer, a frame having a base, a standard rising from the rear margin thereof, a top extending forwardly from said standard and parallel to the base to form a substantially U-shaped frame, an armature depending from the front of said top, an adjusting screw for the armature carried by the standard and a depending boss at the front of the frame 70 pierced to afford a supporting guide for the forward end of the adjusting screw adjacent the armature.

6. In an electromagnetic buzzer, a spring metal armature having a supporting head, 80 and a bar spaced therefrom and integral spring arms connecting said head and bar.

7. In an electromagnetic buzzer, a frame having a base, a standard rising from the rear margin thereof, a top extending forwardly from said standard and parallel to the base to form a substantially U-shaped frame, an armature depending from the front of said top, an adjusting screw carried by the standard and a depending boss 85 at the front of the frame pierced to afford a supporting guide for the forward end of the adjusting screw adjacent the armature, together with a foot piece extension at the forward end-edge of the base, a terminal 90 standard secured to but insulated from said foot piece and a screw contact mounted in said standard and co-operating with the armature, substantially as described.

8. In an electromagnetic buzzer, a spring 100 metal armature having a supporting head and a bar spaced therefrom and integral spring arms connecting said head and bar, together with a tongue projecting from the head area into the space between the arms 105 to afford a bearing abutment for an adjusting screw.

In testimony whereof I have signed my name to this specification.

EDW. SCHWARTZ.
